UNITED STATES PATENT OFFICE.

CARL INGALLS POLLARD, OF PORTSMOUTH, OHIO, ASSIGNOR OF ONE-HALF TO THE VULCAN LAST COMPANY, OF PORTSMOUTH, OHIO, A CORPORATION OF OHIO.

MACHINE FOR FORMING HEELS FOR SHOES.

Application filed July 10, 1923. Serial No. 650,623.

My invention relates to a machine for forming heels for shoes. It is the object of my invention to provide a machine which will form the compound 5 curves on the heel of a shoe. It is a further object of my invention to provide a machine which will embrace varying types of heels of varying sizes and dimensions, and will be adjustable for that 10 purpose without a modification of the machine.

It is an additional object of my invention to provide a machine in which any number of heels may be made in duplicate. 15 It is an additional object to provide a machine which will be adjustable so that the curvature of the heel on the sides and the back may be varied to suit the individual type of heel desired. 20 It is an additional object to provide a cutting means for forming the heel which will give a similar cut to the heel on both sides and on the rear thereof, so that dual cutting means may be provided which will 25 treat both sides of the heel alike.

It is an additional object of my invention to provide means of guiding inwardly and outwardly the heel into engagement with the cutting means at predetermined elevations and angles, and to provide means of 30 adjusting such positions and angles to suit the character of heel it is desired to manufacture.

It is a further object of my invention to 35 provide a machine which will be safe to operate, and in which the cutting means can not easily engage or come in contact with the operator.

It is a further object to provide a mechanism of such a character that the formation 40 of the curves of the heel may be largely automatic, so that different operators on different machines having similar adjustment, or different operators on the same machine, 45 will secure a uniform product.

Referring to the drawings:

Figure 1 is a side elevation of the machine.

Figure 2 is a front elevation of the machine.

Figure 3 is a plan view of the machine.

Figure 4 is a section on the line 4—4 of Figure 3, with the heel holder in full line.

Figure 5 is a diagrammatic plan view of the machine, indicating the various positions of the blank for being worked upon by the cutting means. 55

Figure 6 is a blank.

Figure 7 is a view showing a plan view of the blank. 60

Figure 8 is a view showing the result of the first operation on the blank.

Figure 9 is a view showing the result of the second operation on the blank.

Figure 10 is a perspective of the blank 65 after being finished on the machine.

Figure 11 is a plan view of the machine and its drives.

Figure 12 is a side elevation partially in section, showing a safety driving clutch. 70

In general this machine is operated as follows:

A heel blank is clamped in the clamping jaws, after having been adjusted for the particular size of heel blank to be used. This 75 heel clamp is moved about a central pivot between the cutting knives. The angle at which this blank is held in the holder is determined by the upper track.

The elevation of this holder is determined 80 by the lower track. The angle of the tracks themselves to the vertical, is determined by another adjustment. Cutting knives are provided for working on either side of the heel to a point midway of the rear thereof. 85 The holder itself is so arranged that it may be rotated while resting on its tracks, so as to bring the handle of the holder parallel to the face of the machine, thus securing a semi-circular sweep of the blank on the 90 knives.

With this general description of the machine, the following is a detailed description:

A frame 1 is bolted by the bolts 2 to the floor. The frame consists of a series of vertical and transverse members such as 3. Upon this frame is mounted a table 4 upon which rest and upon which there are supported various mechanisms to be hereinafter described. 100

The holder consists of a base-block 5, which is pivoted at 6, upon a block 7, which is mounted on the top of a vertical standard 8.

5 This standard is guided in the eyes 9 and 10 of a link or yoke 11. The lower end of this vertical member 8 has a hardened steel plate 12, which rests upon the lower track 13. This track in turn is pivoted upon the 10 frame 68 of the machine at 14. The elevation of the track 13 is determined by the set-screw 15, which is adapted to turn in the arm 16 mounted on the frame 68. The set-screw is positioned in the arm 16 by the 15 lock-nut 17.

Returning to the holder and the pivotal mounting of the base-block upon the vertical standard, it will be observed that this block carries a plate 18 having corrugations 19 on 20 the face thereof for engaging with the base of the blank 20. The blank 20 rests upon this block upon these corrugations. An adjustable finger 21 is mounted upon the block adjacent this corrugated plate and held in 25 position by a bolt 22, which works in a slot 23 in the blank-retaining finger 21. This blank-retaining finger is adjusted by the set-screw 24, which works in an eye 25 carried on the upper surface of the base-block. The 30 upwardly and inwardly extending free end of the blank-retaining finger overlaps the forward upper edge of the heel blank 20, and not only serves to position it, but also serves to hold it upon the corrugated plate 18. The 35 upper end of this blank is engaged by the corrugated face 26 of the locking finger 27. Thus the blank is engaged between the two corrugated surfaces and between the plate and the locking finger, while it is positioned 40 by the blank-retaining finger. This blank-locking finger is pivotally mounted upon a diagonally disposed adjustable frame 28 at 29. The pivot 29 is adjustable in the frame 28 because it is so mounted that it may move 45 in the slot 30 in this frame 28. The frame itself is adjustably mounted on the base-block through the bolts 31 and the slot 32 in the frame 28. The upper end of this frame 28 is formed into a head 33 in which there is 50 vertically disposed a slot 34. In this slot there travels a block 35. This block is adjusted and held in position by a screw 36 actuated by a handle 37. The screw turns in a block 38 (see Fig. 1). The block 35 has 55 a transverse member 39 which serves as a shaft upon which is pivoted a cam head 40, carried on the end of the handle 41. This cam engages with the upper surface of the locking finger 27, serving to force it downwardly against the resistance of a helical spring 42, which is connected at one end 43 to the finger 27, and at the other end to the head 33, as at 44.

In operation the position of the pivot 39 60 is adjusted by the screw 36.

The handle is lifted so that the spring 42 may lift the locking finger 27. A blank is placed in position beneath the finger 21, and the handle is lowered so that the cam 40, engaging with 27, will lock the several parts 70 to one another. The adjustment of the handle 37 will determine the degree and nature of the locking engagement.

The whole structure pivots about the pivot 6. The base-block carries a track-engaging 75 plate 45, which rides upon the track 46. This track determines the angle which the entire holder of the blank assumes relatively to the cutting knives. The track itself is pivoted on the frame at 47, and is adjusted by the 80 set-screw 48 working in the arm 49 mounted on the frame 57, in a manner to be herein-after described. This set-screw 48 is locked in position by the lock-nut 50. The frames upon which the tracks 13 and 46 are mounted at 14 and 47 are designated 68 and 57, and are adapted to move vertically on the 85 face of the main frame 1. This adjustment will be hereinafter described. A pair of horizontally disposed supports are slidably 90 mounted in the frame 1. These supports are designated respectively 51 and 52, and are carried in the extended collars 53 and 54 in the frame 1. They are positioned therein by the set-screws 55 and 56. These 95 slidable members 51 and 52 have pivoted thereon the arms 58 and 59 on the pivots 60 and 61. The arms 58 and 59 carry on their outer ends a vertical member 62, which is positioned 100 vertically by the collars 63 and 64 affixed thereto by set-screws 65 and 66. This vertical member carries the link or yoke 11, which in turn supports the vertical standard 8, which determines the elevation in its turn 105 of the block 7, upon which is pivoted the holding mechanism for the blanks. At 67 is designated the arms of the link 11 which engage with the vertical member 62. By varying the adjustment of the supporting 110 members 51 and 52, the lateral position of 110 62 may be controlled, and also its position with respect to the vertical.

The frame 57 consists of a half on each side of the machine, as will be more clearly seen in Figure 2. The frame is vertically 115 adjustable on the bolts 69 which are located in the slots 70 in each half of the frame 57 on each side of the machine. It will be seen that this frame 57 carries the upper track 46 pivotally at 47, and carries the frame 49 120 upon which is mounted the screw 48.

A similar arrangement is found in the frame 68, which is located within the frame 57 on the face of the main frame 1 of the machine. It supports the track 13 and the 125 arm 16. It is also adjustable vertically by means of the bolts 71 operating in the slots 72 in the frame 68.

This vertical adjustment of the frame 57 is effected by the set-screw 73 working in the 130

eyes 74 of the frame 1. Similar set-screws and eyes are on each side of the face of the frame of the machine.

5 A corresponding pair of set-screws designated 75, working in eyes 76 of the frame are provided for actuating the vertical adjustment of the frame 68.

10 Mounted on the vertical standard 8, beneath the block 7, is a collar or plate 77, which is adapted to engage with a horn or stop 78, carried on an arm 79 on top of the machine adjacent the cutting knives in front of the knives.

15 As will be seen not only in Figure 4, but more particularly in Figure 3, this horn or guide is semi-circular and is adapted to engage with the buffer plate 77. The arm 79 is connected to a block at 80, having a slot 81, in which there is located a guiding bolt 20 82 mounted on the top of the table 1. This block is actuated by a screw 83, carried by the table top, or an eye mounted thereon. The screw is actuated by a knurled hand-wheel 84, so that the depth of cut may be 25 determined by this adjusting horn engaging with the buffer plate.

30 As will be seen in Figure 3, the track 13 has a V-shaped vertical depression 85 at the central or neutral position of the holder for the blank. This serves to maintain the holder in its neutral position, away from the knives, and also serves to maintain it in position when the blanks are being changed. As an additional aid for this same purpose, a rigid 35 arm 86 is provided, located between the knives and supported on the table 1 by the bolts 87. Slots 88 are provided in this arm for adjustment on the bolts 87. The free end 89 of this arm 86 engages frictionally 40 with the holder for this purpose.

45 Within the tracks and the supports, there are mounted two similar cutting mechanisms for respectively cutting the respective halves of the heel. These cutters consist of an operating shaft 90 with a lower knife-holding plate 91 and an upper knife-holding plate 92, suitably grooved for engaging the sides of the cutters or knives 93. A lock-nut 94 serves to co-operate with the shoulder 95 for 50 locking the plates and knives to one another on the shaft.

55 The shafts are mounted in suitable bearings carried on the front of the frame, such as those designated 96 and 97, each shaft being downwardly and inwardly tapered as indicated in the dotted lines 98. Upwardly and inwardly tapered pulleys 99 are provided to support belts 100. The belts mounted on the respective pulleys engage 60 with pulley wheels 101 mounted on a common shaft 102 driven by a common motor 103. There is an overload brake pulley or safety clutch which consists, as will be seen in Figure 12, of the shaft 102 working inside of the sleeve 104, which is mounted on

the armature shaft of the motor 103. On this sleeve 104 is mounted a spider having a plurality of arms 105 and laterally projecting pins 106.

70 The shaft 102 carries a cup 107, in which there are located at equal distances a series of laterally projecting pins 108. A short belt 109 passes around the pins 108, so that the pins 106 on the spider engage the portions of the belt between the pins 108. The 75 belt is split at 110, and held together by a lacing 111. If there is any jam in the machinery, the lacing gives away, and the motor and the shafting can operate independently, so that only the lacing breaks, and the 80 machinery itself will not be torn to pieces due to the jam therein.

85 The blank placed in the machine, generally designated 20, is of the form shown in Figure 6. It is provided with a groove 112, an upper surface 113, which is the top of the heel, and a surface 114, which is the bottom of the heel, but when placed in the machine, the heel is placed in it upside down. A sloping surface 115 is toward the 90 rear of the heel.

95 After fixing the blank in the holder, the holder is moved to the position shown in Figure 5 at the right hand side or the left, as may be preferred.

99 The handle swings about the vertical shaft 62, which carries the swinging frame 11, and which in turn supports the vertical standard 8.

100 The entire structure is moved to the position shown and marked A, so that the knives begin to cut that portion of the blank marked b, which is at the forward part of the heel, adjacent the groove 112. At this time, the buffer plate 77 is in engagement 105 with the horn 78. As the handle is moved, the buffer plate 77 rolls on the horn 78 and the knives take a progressive cut from the front of the heel to the rear, to the position marked C, as will be seen in Figure 8.

110 The several adjustments of angularity and vertical position determine the precise curves secured. Upon the completion of the operation at C, the handle is in the position marked D, the holder having remained otherwise bodily adjacent the knives and having been moved on 8 as a pivot. Upon the completion of the operation, the entire holder and handle are moved about 62 as a pivot to the other side for engagement 115 with the other knife, for the finishing of the other side of the blank. Thus the finished heel is secured, as is seen in Figure 10, so far as this machine is designed to work upon 120 the heel.

125 The plate 45 is made sufficiently broad, and is provided with a shoulder 45^a, so that as the blank-supporting means swings in various positions, the plate will always be 130 on the track 46. The shoulder 45^a will pre-

vent a disengagement of it from the track.

The plate 12 on the vertical standard 8 is likewise formed into an arm of some length, so that the plate will always be on the track 13.

The head 28 is held in position by a knurled locking finger 116 engaging with the teeth 117. 116 is held in position by the pin 118 inserted in the block. The pin 119 on the other side of the head is mounted on the block and acts as a stop as well as a guide in the adjustment of the head.

It will be understood that I desire to comprehend within my invention such modifications as may be fairly embraced within it, and as may be found necessary in adapting it to various conditions in the art in the course of the application of the invention.

Having thus fully described my invention, what I claim as new, and desire to secure by Letters Patent, is:

1. In a machine for manufacturing heels, a frame, means for holding a blank, means pivoted on the frame for supporting the holding means, said holding means being transversely pivoted thereon, a cutting means, means for vertically adjusting the position of the holding means about its transverse pivot and means for horizontally adjusting the position of said holding means.

2. In a machine for manufacturing heels, a frame, means for holding a blank, means pivoted on the frame for supporting the holding means, said holding means being transversely pivoted thereon, a cutting means, means for vertically adjusting the position of the holding means about its transverse pivot, means to vertically pivot the holding means with respect to the means which pivotally connects it to the frame, means for adjusting the vertical position of the vertical pivotal means of the holding means, and means permitting lateral adjustment of the vertical pivoting means last mentioned.

3. In a machine for manufacturing heels, a body frame, a work holder, a shaft having said holder horizontally pivoted thereto, a member in which said shaft is rotatably mounted, a vertically adjustable shaft upon which said member is slidably and pivotably mounted, and means for laterally adjusting said adjustable shaft and its supported parts with respect to the frame, and cutting means about which the holder is transversely swung.

4. In a machine for manufacturing heels, a frame, a cutting means mounted thereon, a holding means to hold a blank, a link having a horizontally disposed pivot connected to said holding means, said link being laterally adjustably pivoted on said frame for guiding said holding means and the blank adjacent the cutting means, a track for supporting said holding means as it is moved

relatively to the frame on the link, means to pivot on a vertical axis the holding means on the outer end of the link, and a second track for adjusting the elevation of said vertical pivoting means and the holding means.

5. In a machine for manufacturing heels, a frame, a cutting means mounted thereon, a holding means to hold a blank, a link having a horizontally disposed pivot connected to said holding means, said link being laterally adjustably pivoted on said frame for guiding said holding means and the blank adjacent the cutting means, a track for supporting said holding means as it is moved relatively to the frame on the link to determine the angularity of the holding means, means to pivot on a vertical axis the holding means on the outer end of the link, and a second track for adjusting the elevation of said vertical pivoting means and the holding means, said tracks normally being disposed at a slight angle to the horizontal.

6. In a machine for manufacturing heels, a frame, a cutting means mounted thereon, a holding means to hold a blank, a link having a horizontally disposed pivot connected to said holding means, said link being laterally adjustably pivoted on said frame for guiding said holding means and the blank adjacent the cutting means, a track for supporting said holding means as it is moved relatively to the frame on the link, means to pivot on a vertical axis the holding means on the outer end of the link and a second track for adjusting the elevation of said vertical pivoting means and the holding means, said tracks normally being disposed at a slight angle to the horizontal, and means for adjusting the angularity of said tracks.

7. In a machine for manufacturing heels, a frame, a cutting means mounted thereon, a holding means to hold a blank, a link having a horizontally disposed pivot connected to said holding means, said link being laterally adjustably pivoted on said frame for guiding said holding means and the blank adjacent the cutting means, a track for supporting said holding means as it is moved relatively to the frame on the link, means to pivot on a vertical axis the holding means on the outer end of the link and a second track for adjusting the elevation of said vertical pivoting means and the holding means, said tracks normally being disposed at a slight angle to the horizontal, and means for adjusting the angularity of said tracks.

8. In a machine for manufacturing heels, a frame, a cutting means mounted thereon, a holding means to hold a blank, a link connected with said holding means and laterally adjustably pivoted on said frame for guiding said holding means and its blank adjacent the cutting means, a track for sup-

- porting said holding means as it is moved relatively to the frame on the link, means to pivot on a vertical axis the holding means on the outer end of the link, a second track 5 for adjusting the elevation of said vertical pivoting means and the holding means, said tracks normally being disposed at a slight angle to the horizontal, means for adjusting the angularity of said tracks, means for bodily 10 adjusting either of said tracks, and additional means permitting the adjustment of the vertical position of the vertically pivoting means connecting the link and the holding means to one another.
9. In a machine for manufacturing heels, a supporting body frame, cutting means mounted on the frame, a work holder to hold the blank, a link pivotally connected with the holder and laterally adjustably pivoted to said body frame for guiding said holder and its blank adjacent the cutting means, a pair of vertically adjustable track frames on the body frame, a track pivoted on one of said track frames and supporting 20 said holder as it is moved relatively to the body frame, a second track pivoted to the other frame for adjusting the elevation of the holder, means on the respective track frames for adjusting the angularity of said 25 tracks, and means for moving said holder relative to the tracks into operative engagement with the cutting means.
10. In a machine for manufacturing heels, a supporting body frame, cutting means mounted on the frame, a work holder to hold a heel blank, a link structure pivoted to the body frame and vertically movable relative thereto, said link also being adapted to lateral adjustment relative to said frame, means 30 connecting said link and holder for permitting horizontal and vertical pivotal movement of the holder relative to the cutting means, a pair of track frames on the body frame, a track vertically pivoted to one of 35 said frames for supporting said holder as it is moved relative to the body frame and said cutting means, a second track vertically pivoted to the other track frame and upon which the holder connecting means and link 40 are supported for determining the elevation of said holder, adjusting means on each of said track frames for varying the angularity of the tracks, means for bodily adjusting either of said track frames, and means 45 for moving the holder relative to the track into engagement with said cutting means.
11. In a machine for manufacturing heels, a frame, a cutting means mounted thereon, a track, a blank-holding means adapted to 50 slide on said track, a link pivoted on said frame and vertically pivoted to said holding means, means to transversely pivot said holding means with respect to its vertical pivot, a second track to determine the elevation of 55 the vertically pivoting means, said tracks being semi-circular and said cutting means being disposed on both sides of the frame adjacent the ends of said track, whereby the blank will be presented at a predetermined angle to the cutting means at a predetermined elevation, and may be rotated with respect thereto, and means on one of said tracks for locating said holding means in a neutral position.
12. In a machine for manufacturing heels, 70 a frame, a cutting means mounted thereon, a track, a blank-holding means adapted to slide on said track, a link pivoted on said frame and vertically pivoted to said holding means, means to transversely pivot said holding means with respect to its vertical pivot, a second track to determine the elevation of the vertically pivoting means, said tracks being semi-circular and said cutting means being disposed on both sides of the frame adjacent the ends of said tracks, whereby the blank will be presented at a predetermined angle to the cutting means at a predetermined elevation, and may be rotated with respect thereto, means on one of said tracks for locating said holding means in a neutral position, and means to prevent the holding means when in a neutral position from coming in engagement with the cutting means.
13. In a machine for manufacturing heels, 95 a blank-holding means comprising a support, a base-block horizontally pivoted to the support and provided with a work-engaging face, a member longitudinally movable on the base-block in a direction normal to the work-engaging face, said member having an angularly disposed head projecting over said face, means for holding said member in adjusted relation to the base-block, a blank-positioning finger pivoted in said head and provided with a work-engaging face to cooperate with the work-engaging face of the base-block, an element adjustable in said head, and a lever pivoted to said element and 100 having a cam to engage the free end of the finger, said lever and cam being operative to move the finger to force together the work-engaging faces.
14. In a machine for manufacturing heels, 115 a blank-holding means comprising a support, a base-block horizontally pivoted to the support and provided with a work-engaging face, a member adjustably mounted on said base-block to be longitudinally movable 120 thereon in a direction approximately normal to the work-engaging face of the base-block, said member having an angularly disposed head projecting over said face, means for holding said member in its adjustments on the base-block, a blank-positioning finger movably mounted in said head and provided with a work-engaging face to cooperate with the work-engaging face of the base-block, 125 said finger being pivoted in transverse slots 130

in said member to permit movement of its work-engaging face across the work-engaging face of the base-block, an element adjustable in said head, a lever pivoted in said head to said element and having a cam to engage the free end of the positioning finger, said lever and cam being operative to

move the positioning finger to force together the work-engaging faces, and a spring normally tending to move the finger against the 10 action of the cam.

In testimony whereof, I affix my signature.

CARL INGALLS POLLARD.
